MUSICAL INSTRUMENT AND CONTROL CART

Mark Saltzman, Stoneybrook, N.Y., assignor to Sorkin
Music Company Inc., Hauppauge, N.Y.

Filed July 14, 1972, Ser. No. 271,790

Term of patent 14 years

Int. Cl. D12—02; D6—06
U.S. Cl. D14—3 MFIG. 1

FIG. 2

FIG. 3

FIG. 1 is a perspective view of a musical instrument and control cart embodying my new design;

FIG. 2 is a top plan view thereof; and

FIG. 3 is an end elevational view thereof, taken from the opposite end to that shown in FIG. 1.

I claim:

The ornamental design for a musical instrument and control cart, as shown.
